DESIGN FOR A FRAME FOR BICYCLES

Charles E. Bruce, Memphis, Tenn., assignor of
one-fourth to Charles G. Johnson, Memphis,
Tenn., and one-fourth to Arjoree Dell Cauthen,
Dallas, Tex.

Application August 23, 1945, Serial No. 121,591

Term of patent 7 years

(CL. D90—8)

To all whom it may concern:

Be it known that I, Charles E. Bruce, a citizen
of the United States, residing at Memphis, in the
county of Shelby and State of Tennessee, have
invented a new, original, and ornamental Design
for a Frame for Bicycles, of which the following
is a specification, reference being had to the ac-
companying drawing, forming part thereof.

In the drawing,

Fig. 1 is a side elevational view of a frame for
bicycles showing my new design; and

Fig. 2 is a top plan view thereof.

I claim:

The ornamental design for a frame for bicycles,
as shown.

CHARLES E. BRUCE.
